DESIGN FOR AN ADJUSTABLE LETTERING DEVICE

John A. Truhon, Detroit, Mich.

Application September 9, 1944, Serial No. 115,242

Term of patent 14 years

(Cl. D52—1)

To all whom it may concern:

Be it known that I, John A. Truhon, a citizen of the United States of America, residing at Detroit, in the county of Wayne, State of Michigan, have invented a new, original, and ornamental Design for Adjustable Lettering Device, of which the following is a specification, reference being had to the accompanying drawing, forming a part thereof, wherein:

Fig. 1 is a plan view of an adjustable lettering device showing my new design;

Fig. 2 is a transverse sectional view taken on the line 2—2 of Fig. 1;

Fig. 3 is a transverse sectional view taken on the line 3—3 of Fig. 1; and,

Fig. 4 is a transverse sectional view taken on the line 4—4 of Fig. 1.

I claim:

The ornamental design for an adjustable lettering device, as shown.

JOHN A. TRUHON.
